UNITED STATES PATENT OFFICE.

GEORGE L. MOORE, OF BETHLEHEM, PENNSYLVANIA, ASSIGNOR TO MOORE & STEELE CORPORATION, A CORPORATION OF DELAWARE.

RAIL ANCHOR.

Application filed April 15, 1926. Serial No. 102,174.

The invention relates to rail-anchors, and comprises a rigid or comparatively rigid yoke in combination with a strong spring member carried by the under-rail portion of the yoke and adjustable thereon, the assemblage being driven transversely of the rail to position thereon, the distortion of the powerful spring member between the yoke and the bottom of the rail producing an 10 relaxing grip between the end jaws of the yoke and the spring member on the top and bottom of the rail-base.

The spring member is positionable at any one of a series of two or more seats along the under-rail portion of the yoke, the construction being such that this varies the height at which the spring member rests on the yoke, thereby affording a take-up for wear and an adjustment for variation in size 20 of rails.

In the accompanying drawing forming a part hereof:

Fig. 1 is a cross-section through a rail, showing the rail-anchor in preliminary position thereon, preparatory to driving;

Fig. 2 is a similar view, with the upper part of the rail omitted, showing the anchor partly driven onto the rail, the condition being that of maximum distortion and tension having been put into the spring member;

Fig. 3 is a view like Fig. 2, showing the rail-anchor in final position;

Fig. 4 is a side elevation of a portion of the rail resting on a fragment of the tie, showing the rail-anchor in end view abutting the tie;

Fig. 5 is an elevation of the yoke; and

Fig. 6 is a bottom plan view of the spring member.

The yoke 2 comprises an under-rail portion 3 and end jaws 4, 5, the whole being preferably cut or punched from a fairly heavy plate and being rigid or substantially so. The end jaws are intended to engage over the rail-base flanges, while the under-rail portion of the yoke is to be spaced considerably below the bottom of the rail. The jaws 4, 5 are of unequal length, due to the fact that the interior space of the yoke is formed with sufficient clearance below the jaw 4 to permit the yoke, with the spring member thereon which will be described, to be hooked laterally onto a rail in place, to be brought to a preliminary or predriving

position, as shown in Fig. 1. The anchor is then driven to its holding or gripping position in a direction transversely of the rail.

The short jaw 5 has a steeply sloped nose 6, which in preliminary position rests 60 against the edge of the rail, requiring this end of the yoke to rise sharply in order to drive the bottom bearing point 7 of the nose up onto the top of the rail-flange, to the position seen in Fig. 2, where this point is just 65 over the edge of the rail.

Saddled on the under-rail portion or bar is an elongated member 8 of spring material, this member constituting a very strong and powerful spring. The two ends 9, 10 of this member are preferably provided with pairs of bottom ears, so as to be retained on the under-rail portion, and between these ends the member extends in a low, broad arch, 75 clear of the under-rail portion 3. The space 75 or clearance 11 between the body of the spring member and the under-rail portion 3 remains at all times when the anchor is being driven on the rail and when it is in final position.

The forward end 9 of the spring member has a central lug 12, which is adapted to engage in any one of a series of seat notches 13 formed in the forward part of the upper side of the under-rail member 3, these seats being formed in co-operation with said lug with square shoulders front and back, so as to hold the spring member from shifting rearward on the yoke when the yoke is driven onto the rail, and also to hold the spring member against shifting in the opposite direction relative to the yoke.

The relations are such that the member 8 receives its maximum tension and distortion when the anchor has been driven far enough to carry the bearing point 7 up over the edge of the rail-flange. Thereafter, as the anchor is driven the remaining distance by blows applied to the end of the yoke, causing the anchor to reach its final position of Fig. 3, the distortion of the spring member is not increased, but is preferably slightly diminished. This is due to the cam formation of the top of the member 8, and to the fact that the place of bearing of the spring member against the bottom of the rail is always at least as near to the place of bearing of the long jaw 4 on top of the rail-base as to the place of bearing of the short jaw 5. 105 Indeed, as shown, the place of bearing of the 110

spring member is nearer to the long jaw bearing than it is to the short jaw bearing. Consequently, in the latter half or part of the driving, the long or forward jaw tends to ride down on the slope of the rail-flange faster than the contact point 7 rides up on the slope of the other rail-flange, in progressing from the intermediate position of Fig. 2 to the final position of Fig. 3. This would loosen the anchor, were it not for the excess distortion put into the spring in driving from the position of Fig. 1 to that of Fig. 2, during which the steep slope 6 of the short jaw was mounting up on the edge 15 of the rail-flange. The exact conditions are difficult to illustrate in the drawing, but it may be understood that in Fig. 1 the spring has not been distorted, in Fig. 2 it has its maximum distortion, and that in Fig. 3 its distortion has not been increased but, on the contrary, has been reduced somewhat, still exerting ample spring force to grip the anchor firmly on the rail and to prevent the rail from creeping while the anchor abuts 25 against the tie.

A great drawback about many styles of rail-anchors is that they do not provide a satisfactory take-up, to afford adjustment for wear or for variation in rails of a given 30 size. The present invention has a very effective, wide-range take-up, it being merely necessary to shift the spring or bottom-contact member to one or another of the seat notches 13 nearer the long-jaw end of the 35 yoke, to accommodate the device to a somewhat smaller or more worn rail-base. When the member is displaced in this direction, its rear end is positioned further up a slope 14 on the bar 3, so that the device will be able 40 to apply a powerful grip to the smaller or worn rail, the spring member then standing higher on the under-rail portion of the yoke than it does in the drawing, where it occupies the lowest position, suitable for a 45 larger or un-worn rail. This take-up is especially advantageous for taking care of the reduction in thickness of a rail-base, by corrosion, tie-plate wear, brine-drip, etc., which is likely to vary from one thirty-second to 50 one-sixteenth of an inch after a rail has been in service from five to eight years, and which in some cases may amount to as much as an eighth of an inch. Also, rails when new are not always made to a precise size.

55 While the preferred embodiment of the invention has been described in detail, it will be understood that there may be various changes in form and detail, and in the specific mode of operation.

60 **I claim:**

1. A rail-anchor, comprising a substantially rigid yoke formed with end jaws to engage over the base flanges of a rail and a transverse under-rail portion to lie spaced 65 below the bottom of the rail, in combination

with a strong spring member mounted on the under-rail portion so as to be carried thereby when the yoke is driven transversely to its position on the rail, said spring member being thereby distorted between the under-rail portion of the yoke and the bottom of the rail, producing a powerful gripping action of the jaws and spring member on the top and bottom of the rail-base, the effective grip of the anchor on the rail resulting from the driving of the yoke transversely of the rail substantially as specified.

2. A rail-anchor, comprising a substantially rigid yoke formed with end jaws to engage over the base flanges of a rail and a transverse under-rail portion to lie spaced below the bottom of the rail, in combination with a strong spring member mounted on said under-rail portion so as to be carried thereby when the yoke is driven transversely to its position on the rail, said spring member being thereby distorted between the under-rail portion of the yoke and the bottom of the rail, producing a powerful gripping action of the jaws and spring member on the top and bottom of the rail-base, said under-rail portion having a plurality of retaining seats for retaining the spring member in different positions, substantially as and for the purpose set forth.

3. A rail-anchor, comprising a substantially rigid yoke formed with end jaws to engage over the base flanges of a rail and a transverse under-rail portion to lie spaced below the bottom of the rail, in combination with a strong spring member mounted on said under-rail portion so as to be carried thereby when the yoke is driven transversely to its position on the rail, said spring member to be distorted between the under-rail portion of the yoke and the bottom of the rail, producing a powerful gripping action of the jaws and spring member on the top and bottom of the rail-base, the construction being such that the spring member receives its maximum distortion during a part of the driving of the anchor onto the rail, such distortion and the resulting pressure not being increased during further driving, substantially as set forth.

4. A rail-anchor, comprising a substantially rigid yoke formed with end jaws to engage over the base flanges of a rail and a transverse under-rail portion to lie spaced below the bottom of the rail, in combination with a strong spring member mounted on said under-rail portion so as to be carried thereby when the yoke is driven transversely to its position on the rail, said spring member to be distorted between the under-rail portion of the yoke and the bottom of the rail, producing a powerful gripping action of the jaws and spring member on the top and bottom of the rail-base, the construction being such that the spring member receives

its maximum distortion during a part of the driving of the anchor onto the rail, further driving diminishing the distortion to some extent, substantially as set forth.

- 5 5. A rail-anchor which obtains its working grip on the rail by being driven transversely of the rail, comprising a yoke formed with end jaws to engage over the base flanges of a rail and a transverse under-rail portion 10 to lie below the bottom of the rail, in combination with a strong spring member mounted on said under-rail portion to bear against the bottom of the rail, said under-rail portion having a retaining seat for said 15 spring member whereby said spring member is carried with the yoke in definite position thereon during the driving in the transverse direction.
6. A rail-anchor which obtains its working grip on the rail by being driven transversely of the rail, comprising a yoke formed with end jaws to engage over the base flanges of a rail and a transverse under-rail portion to lie below the bottom of the rail,

in combination with a strong spring member 25 mounted on said under-rail portion to bear against the bottom of the rail, said spring-member engaging said under-rail portion in such manner as to be carried with the yoke 30 in definite position thereon during the driving in the transverse direction and being also retained on the yoke against displacement relative thereto longitudinally of the rail.

7. A rail-anchor which obtains its working grip on the rail by being driven transversely of the rail, comprising a yoke formed with end jaws to engage over the base flanges of a rail and a transverse under-rail portion to lie below the bottom of the rail, in combination with a strong spring member mounted on and lying lengthwise of said under-rail portion to bear against the bottom of the rail, said under-rail portion having a retaining seat for said spring member whereby 40 said spring member is carried with the yoke 45 in definite position thereon during the driving in the transverse direction.

GEORGE L. MOORE.
